UNITED STATES PATENT OFFICE.

JOSEPH L. WRIGHT, OF CLEVELAND, OHIO, ASSIGNOR TO JAMES R. GARFIELD,
TRUSTEE, OF CLEVELAND, OHIO.

TELEPHONE-EXCHANGE SYSTEM.

Original application filed February 26, 1912. Serial No. 680,015. Patent No. 1,244,571, dated October 30, 1917. Divided and this application filed July 12, 1917. Serial No. 180,131.

To all whom it may concern:

Be it known that I, JOSEPH L. WRIGHT, a citizen of the United States, residing at Cleveland, in the county of Cuyahoga and State of Ohio, have invented certain new and useful Improvements in Telephone-Exchange Systems, of which the following is a full, clear, concise, and exact description.

This invention relates to telephone exchange systems, and especially to semi-automatic systems, which employ switching mechanism controlled by operators for effecting connections between subscribers.

This application is a division of my application 680,015, filed February 26, 1912, Patent No. 1,244,571, granted October 30, 1917.

The main feature of this invention is the provision of means to dispense with the operator's transmitter so that it will be unnecessary for her to ask the number of the wanted party, since this operation is automatically performed.

My invention is illustrated in the accompanying drawings, wherein Fig. 1 shows a subscriber's line equipment and control circuit; Fig. 2 shows a primary and first selector circuit; Fig. 3 shows a key set control circuit together with a time element controlling device or kick-off switch; Fig. 4 shows the circuit of the operator's key set switch and its associated shifting switch; and Fig. 5 shows an operator's keyboard and sending device.

The subscriber at A, upon removing his receiver, closes the circuit of the line relay 2 in series with the group relay 3. This latter relay operating closes the circuit of relay 4, which in turn connects ground to one terminal of the relay 5, and also closes the circuit of the stepping magnet 7. The stepping magnet 7 operating closes the circuit of relay 6, which in turn opens the circuit of the magnet, causing it to vibrate and step around the wipers of the switch W. This switch will continue to rotate until an idle primary switch, such as shown at C (Fig. 2), is found. As soon as such an idle switch is found, relay 5 is placed in series with relay 21 (Fig. 2), by the following path: ground, contact of relay 4, 5, 18, left-hand armature and contact of relay 76 (Fig. 3), 148, upper bank of switch W, 14, 21, 70, inner right-hand back contact and armature of relay 24

to battery B. The relay 5 becoming energized opens the circuit of the stepping magnet 7, bringing the switch W to rest. Relay 21 operating closes the circuit of the rotary stepping magnet 31 by the following path: battery B, outer right-hand contact of relay 21, 80, back contact of relay 24, 71, contact of relay 28, back contact of relay 22, winding of magnet 31 to ground. The operation of magnet 31 causes the primary switch C to rotate until the wiper 64 reaches the busy contact, to which is connected wire 13, leading to the contacts of relay 3.

The wiper 64 is carried on the same spindle with wipers 63 and 65, and while the switch is rotating, the wiper 64 passes over contacts rendered busy by the action of relay 3. As there are ten of these group relays to each one hundred lines, it follows that the wiper 64, to reach its extreme position, passes over ten contacts.

There are ten sets of individual contacts arranged in vertical rows, associated with each row contact, and which the wipers 63 and 65 respectively engage. It, therefore, follows that after the switch picks out the group in which a line is calling, it will afterward step vertically until the wipers engage the contacts of the calling line.

As soon as the row contact is found, the circuit of relay 22 is closed as follows: battery B, outer right-hand armature and contact of relay 21, 80, left-hand armature and contact of relay 24, 71, winding of relay 22, 64, 13, contact and left-hand armature of relay 3 to ground. The relay 22 operating disconnects the rotary magnet 31, and in its place connects the vertical magnet 30, thereby causing the switch to step vertically until the busy individual test contact is found. As soon as such a contact is found, the circuit of relay 24 is closed by the following path: battery B, winding of relay 24, 68, 67, 11, contacts and armature of relay 2 to ground through the contacts of relay 1. The relay 24 operating opens the wire 71, disconnecting relay 22, which in falling back disconnects relay 24 from wire 67 and connects it instead to wire 66. The relay 24 is now placed in series with relay 1 and the operating of this latter relay disconnects line relay 2 and the group relay 3. The operating of relay 24 connects battery to the windings of relays 23 and 25, and the falling back of re-

lay 22 connects ground to the retardation coil 26, and battery is thereby supplied to the calling subscriber for talking purposes through the windings of relay 23 and retardation coil 26.

The relay 21 remains energized until the primary switch finds the calling line, and until the key-set switch finds the calling trunk. The relay 21 when first actuated 10 places battery on the wire 79 to relay 130 to ground, and also places battery to wire 62 leading to the individual test contact of the key-set switch (Fig. 4).

The relay 130 operating closes the circuits of the stepping magnet 133 of the switch Y through the normally closed contacts of relays 131 and 132. The switch magnet 133 in operating closes the circuit of the interrupter relay 134, which causes 20 a vibrating effect between the magnet and the relay, and the switch will continue to rotate until an idle key-set switch is found. When such a switch is found, as shown in Fig. 4, relay 131 is placed in series with 25 relay 152 (Fig. 4) by the following path: ground, contacts of relay 130, 131, 138, through the bank contacts of Y, 140, 152, 195, 196, 197, to battery through the operator's jack 400.

30 Relay 131 operating places battery on wire 136 to relay 132, causing it to operate. As soon as this latter relay operates, it places ground on wire 130', thereby shunting relay 131. This direct ground makes the wire 35 140, which is multiplied to other Y switches, busy. The operating of relay 132 also places ground on the row wiper of the key-set switch by the following path: ground, 139, bank contacts of Y, 141, to the row contact 40 (Fig. 4). Relay 152 operating, places ground on the rotary magnet 165, through the back contact of relay 153; thereby causing the switch M to rotate. This switch will continue to rotate until the contact row 45 is found, whereupon the circuit of the relay 153 is closed by the following path: battery B, contacts of relay 152, 176, 153, 171, 168, 141, 139, contacts of relay 132 to ground.

The switch element X serves as a time element control switch and comes into action 50 when the relay 130 and the relay 132 have been held energized beyond the maximum time limit. The relay 132 is energized as soon as an idle key-set switch is picked out, 55 and should only remain energized long enough for the key-set switch (Fig. 4) to pick out the tenth contact in the tenth row. The magnet 77 causes the switch X to rotate when contact springs 36 are closed by a 60 suitable cam on the sending device. These contacts are closed once at each rotation of the sending device.

If the key-set switch M fails to operate in the time allotted, the release magnet 166 65 of the key-set switch M is operated to release

this switch. This energizing circuit may be traced from battery B, winding of the release magnet 166, conductor 142, conductor 144, inner right-hand front contact and armature of relay 76, which is now energized, to ground. This switch X, however, performs no functions in normal connections unless the key-set switch M and trunk should become "tied up," whereupon it operates and releases the "tied up" apparatus. 70 75

The action of the key-set switch M is identical with that of the primary selector switch C (Fig. 2).

The operating of relay 153 disconnects the rotary magnet 165 and in its place connects 80 the vertical magnet 164, thereby causing the key-set switch to step vertically until the busy individual test contact is found. As soon as this contact is found, the circuit of the relay 154 is closed as follows: ground, 85 154, 172, 62, 80, contacts of relay 21 to battery B. The operating of relay 154 disconnects relay 152, thereby cutting off the vertical magnet causing the key-set switch M to rest on contacts leading to the calling 90 primary trunk (Fig. 2). Relay 152 becoming disconnected opens the circuit of relay 153, and this latter relay in falling back places relays 156 and 25 in series by the following path: ground, back contact of 95 relay 153, 175, back contact of relay 157, 202, contacts of relay 155 winding of relay 156, 193, contacts of relay 158, 170, 169, 59, 25, to battery B through the contacts of relay 24. The operating of relay 25 disconnects relay 21 and relay 5 (Fig. 1). The releasing of relay 5 frees the switch W, 100 allowing it to pick out other primary switches. Releasing of relay 5 completes the circuit of stepping magnet 7 so that it 105 can again be operated by the energization of relay 4.

Relay 156 operating, places battery on wires 181 and 183, thereby lighting the two lamps 243 and 244 (Fig. 5).

As soon as relay 21, in Fig. 2, became disconnected, battery was removed from the individual test contact of the key-set switch, thereby allowing the relay 154 to fall back. The deenergization of relay 21 also opens 115 the circuit of relay 130, which in turn opens the circuit of relay 132, and allows the switch Y to be used by other trunks in picking out key-set switches.

The lighting of the two lamps 243 and 120 244 notifies the operator of a call. She then presses the button 248, operating relay 155, thereby connecting the operator's telephone set across the tip and sleeve conductors of the trunk. The action of relay 155 disconnects relay 156, extinguishing lamps 243 and 244, but at the same time lighting the lamp 245. The relay 156 becoming disconnected 125 allows relay 25 of Fig. 2 to deenergize, closing the tip and sleeve conductors of the 130

primary trunk and allowing the calling subscriber to converse with the operator. When the operator presses the answering or listening button 248, which is of the non-locking type, and while in the depressed position, a tone test is connected to the primary of the induction coil and from there to the secondary to the calling line. The operation of the button 248 causes the energization of relay 155. The operation of this relay 155 connects the tone test from 880 the contacts of button 248 and contacts of relay 155 to the sleeve side of the operator's trunk extending to the wiper and contact to the wire 61 which extends to the sleeve side of the primary trunk Figure 2. The calling subscriber hearing this tone test, knows that the operator is ready to receive his call and at once gives the number desired. Any suitable tone test arrangement may be employed, such as is shown at 881, in Fig. 4. This tone test is provided with a constantly operating commutator 870, which makes and breaks the circuit of the primary of the transformer 875. The secondary of the transformer in turn has its circuit interrupted by a suitable make-and-break device 880, which produces a musical tone when connected to the primary of the operator's induction coil. With the foregoing arrangement the duties of the operator are simplified and the efficiency of the apparatus is increased, as the operator cannot converse with the calling subscriber. The subscribers in turn know that they cannot converse with the operators and will give their numbers promptly upon getting the proper signal, thereby reducing all delays. It will also be noticed with either arrangement, as shown, that when the calling subscriber is giving his number the primary of the operator's induction coil is opened, thus preventing her hearing the noises in the operating room which ordinarily are taken up by the transmitter, and she can, therefore, hear the calling subscriber more distinctly.

The operator, after getting the proper number from the calling subscriber, presses one button in each row corresponding to the number desired and then presses the starting button 247, which closes the circuit of relay 157 by the following path: ground, 247, 186, 157, 193, 170, 169, 59, 25, to battery B through the contacts of relay 24. The relay 25 again operating opens the trunk conductors to prevent the calling subscriber from hearing the impulses.

The operation of relay 157 disconnects the relay 156, extinguishes lamp 245 and causes the guard lamp 244 to light. The action of this relay also connects the starting wire 189 connected to the contacts operated by the cam 231 to the stepping magnet 161. As soon as the cam contact springs 65 are operated, the wipers of the shifting

switch at N, O, P take one step and connect the impulse wire 191 to the tip side of the trunk 150 through the contacts of relay 160.

If No. 9 button in the row R is pressed, the relay 160 will be held energized by the 70 operation of the cam 240 until nine impulses have been transmitted by the commutator 242. These impulses operate the rotary relay 29 (Fig. 2) by the following path: ground, 242, 191, 190, contacts of relay 160, 75 198, N, 150, 167, 60, 54, 29, 42, cam springs 40 to battery B. The relay 29 responding to these impulses, closes the circuit of the rotary magnet 34, causing the first selector switch D to rotate and come opposite a 80 group of trunks in the ninth row. As soon as the springs operated by the rotary magnet 34 are closed, ground is at once placed between the winding of relay 29 and coil 42, thereby shunting out relay 29, and this relay 85 falling back removes battery from the winding of the magnet 34 itself. It will be noticed that if the impulse from the sending device had been a trifle long, the relay 29 would be shunted out just as soon as the 90 magnet 34 finishes its stroke.

After these rotary impulses have been sent, the starting cam causes the shifting switch to take another step, thereby connecting wire 198 to the sleeve side of trunk 151. 95 The relay 160 is now held up by the action of the cam 230 until a single impulse is transmitted. This impulse operates the relay 27 (Fig. 2) by the following path: ground, 242, 191, 190, 192, contacts of relay 100 160, 198, N, 151, 167, 61, relay 27, cam springs 40 to battery B.

The relay 27 receiving this impulse, is held energized by the following path: battery B, contacts of relay 25, locking contacts of 105 relay 27, 58, contacts of relay 28, 72, 32, 75, cam springs 41 to ground. These cam springs were operated when the switch D took its first rotary motion. The operating of relay 27 closes the circuit of the vertical 110 magnet 33, by the following path: battery B, contacts of relay 28, 711, contacts of relay 27, 33 to ground. The magnet 33 in operating closes the circuit of the relay 28, which in turn opens the circuit of the magnet 33 115 itself. The action of this relay and magnet causes the latter to vibrate, stepping the switch D vertically. When the circuit of relay 28 is closed by the action of the magnet 33, the circuit of relay 27 is itself partially 120 opened but it will remain energized by the test wiper 57 in passing over grounded or busy contacts, for while the magnet 28 is operated and the wiper 57 comes to rest on an idle contact, the relay 27 will at once become deenergized and disconnect the vertical magnet 33.

The controlling of the test relay 27 in the foregoing manner, insures a full step of the magnet 33, as the wiper 57 fully engages the 125 130

test contacts before the relay 27 is opened by the action of relay 28.

As soon as the switch D takes its first vertical step, or while it is in the act of taking 5 this step, the cam springs 40 are opened, thereby disconnecting relays 27 and 29 respectively from the tip and sleeve sides of the trunk. After the test wiper 57 picks out an idle trunk, the subscriber is connected to 10 an idle selecting switch (not shown).

At succeeding rotations of the sending device, impulses corresponding to the hundreds, tens and units digits are sent over the tip side of the trunk.

15 The succeeding selector and connector switches (not shown) are operated in a manner similar to the operation of the primary selector D under the control of the sending device.

20 At the last rotation of the sending devices the relay 158 of Fig. 4 is connected to battery, through the bank P, and the actuation of this relay places ground on magnet 161 and also unlocks relay 157. The magnet 161 25 vibrates rapidly and causes the shifting switch to rotate until the wipers reach their normal or resting position. Just before reaching the normal position, the wiper of bank P places the relay 158 in series with 30 the release magnet 166, thereby causing the switch M to restore. This switch restoring disconnects the operator's key set from the primary trunk and it is immediately available for other calls.

35 The calling subscriber by hanging up his receiver causes the relay 23 (Fig. 2) to fall back as the circuit of the line is open and relay 23 fails to receive current and thereupon becomes deenergized, thereby closing 40 the circuit of the release magnet 32 by the following path: battery B, cams 38, 73, contact of relay 23, 58, 72, 32, 75, cam springs 41, to ground. Magnet 32 operating releases the primary switch C, and this switch in re-

45 turning opens the cam springs 38, thereby removing the shunt from magnet 35 and allowing it to become energized as follows: battery B, 35, 73, contacts of relay 23, 58, 58', 72, 32, 75, cam springs 41, to ground.

50 This operates the release magnet 35 and causes the first selector switch D to restore, opening the cam springs 41 and opening the circuit of magnet 35.

In disclosing the present invention non- 55 numerical switches have been shown for extending a calling line to an operator's position. It will be understood that this connection may also be established manually without departing from the spirit of this 60 invention.

What is claimed is:

1. In a telephone system, the combination with subscribers' lines, of an operator's receiver circuit, a second circuit, a transformer 65 and interrupting means in said second cir-

cuit for producing a musical tone, means for simultaneously connecting the circuits to a subscriber's line to sound the tone test on said line, means for controlling the connecting means, and means for disconnecting 70 the second circuit on release of the controlling means.

2. In a telephone system, the combination with subscribers' lines, of an operator's receiver circuit, means for connecting the operator's receiver circuit to a calling subscriber's line, a second circuit associated with the operator's receiver circuit and comprising a transformer having a primary circuit and a secondary circuit, interrupting means 80 in the primary circuit, other interrupting means in the secondary circuit, means for operating the interrupting means, means for closing the second circuit simultaneously with the connection of the operator's receiver circuit to the line, and means operable on the release of the closing means for disconnecting the second circuit.

3. In a telephone exchange system comprising circuits available for calling purposes, an operator's position, an operator's receiver circuit at said position common to said circuits, automatic switching mechanism for extending said circuits to said operator's position, a device for interrupting 90 said operator's receiver circuit, and means under control of the operator for connecting said interrupted receiver circuit to a calling subscriber's line indicating that said line is connected to said operator's position. 95

4. In a telephone system, the combination with calling telephone lines, of line relays for said lines and switching mechanism controlled thereby for finding said lines, and an electrical emergency device rendered operable by the operation of any of said line relays and prevented from operating by the operation of said switching mechanism. 105

5. In a telephone system, the combination with calling telephone lines, of line relays 110 for said lines and switching mechanism controlled thereby for finding said lines, a relay having an energizing circuit closed by the operation of any of said line relays, means made operative in the operation of said switching mechanism for rendering said energizing circuit ineffective, and slow-acting electrical emergency mechanism controlled by said relay. 115

6. In a call distributing system, the combination with a plurality of lines and a plurality of finder switches for making connection therewith, of a starting relay for starting the movement of a finder switch to connect with a calling line, a controlling circuit for said starting relay, means responsive to the initiation of a call for altering the electrical condition of said controlling circuit to operate said starting relay, an electrical emergency device, a timing device for 120 125 128

operating the same a predetermined interval after the electrical condition of said controlling circuit is altered, and means for preventing the operation of said emergency device made active in the operation of said starting relay.

7. In a call distributing system, the combination with a plurality of lines and a finder switch for making connection therewith, of a starting relay for said finder switch, an electrical emergency device, a controlling circuit for said starting relay and said emergency device, means responsive to the initiation of a call for altering the electrical conditions of said controlling circuit to operate said starting relay first and said emergency device a predetermined interval thereafter, and means for preventing the operating of said emergency device made operative in the actuation of said starting relay.

8. In a telephone system, the combination with a plurality of call-extending circuits and a plurality of operators' positions, of position-selecting apparatus common to said circuits and positions, an energizing circuit for said position-selecting apparatus,

an electrical emergency device, means associated with each call-extending circuit for closing said energizing circuit, and a definite 30 interval thereafter operating said emergency device, and means made active in the operation of said position-selecting apparatus for preventing the operation of said emergency device.

9. In a telephone system, the combination with a plurality of call-extending circuits, of a position selecting apparatus common thereto, an energizing circuit for said position selecting apparatus, means under 40 the control of each of said call-extending circuits for closing said energizing circuit, means made operative in the operation of said position-selecting apparatus for opening said energizing circuit, an electrical 45 emergency device and means for operating the same made effective by the closure of said energizing circuit for longer than the normal interval required for the operation of said position-selecting apparatus.

In witness whereof, I hereunto subscribe my name this 5th day of July A. D., 1917.

JOSEPH L. WRIGHT.
